UNITED STATES PATENT OFFICE.

FRANK L. O. WADSWORTH, OF PITTSBURGH, PENNSYLVANIA, ASSIGNOR TO BALL BROTHERS GLASS MANUFACTURING COMPANY, OF MUNCIE, INDIANA, A CORPORATION OF INDIANA.

GLASS-WORKING MACHINE.

1,375,336.

Specification of Letters Patent. Patented Apr. 19, 1921.

Application filed June 27, 1918. Serial No. 242,266.

To all whom it may concern:

Be it known that I, FRANK L. O. WADSWORTH, a citizen of the United States, residing at Pittsburgh, in the county of Allegheny and State of Pennsylvania, have invented a new and useful Glass-Working Machine, of which the following is a specification.

My invention relates in general to means for automatically charging a series of mold receptacles with molten vitreous material which is delivered thereto in a stream that flows directly from a tank or other large source of supply; and it relates particularly to the severing and manipulation of the flowing stream in such manner that the viscosity and surface tension of the vitreous material is utilized in temporarily arresting the flow of the metal at predetermined intervals for periods sufficiently long to permit the removal of a full mold and the bringing of an empty mold to the charging position.

The primary objects of my improvements in this art are: The avoidance of surface chilling of the glass, which results from the support of any part of the hot stream of material—during either its periods of flow or its periods of arrest—on metal surfaces; the elimination of “laps” and entrained air or gas bubbles and “blisters” which are produced whenever the glass is allowed to pile up on a cutting knife or other surface intermediate between the delivery orifice and the receiving receptacle; and the maintenance of the main body of the flowing metal at all times at a uniform minimum working temperature.

Other objects of my invention are the provision of improved mechanism for very rapidly severing the stream of material at the required predetermined intervals of mold movement; for symmetrically shaping the severed end of the stream (relative to the delivery orifice), to the form which will render the practice of my improved method most effective; and for then instantly withdrawing the severing and shaping means from contact with the hot glass so as to avoid any appreciable chilling beneath the surface of the latter. Still another object of my improvements is to construct the stream-cutting parts of such material and in such manner as to greatly reduce the con-

duction of heat from the hot glass to the 55 cooler metal parts of the mechanism. Still other objects and advantages of my invention will be apparent to those skilled in the art to whom this disclosure is particularly addressed.

In the accompanying drawings, Figure 1 illustrates, in sectional elevation, one form of mechanism adapted to practice my invention; Fig. 2 is a similar section of the same mechanism showing the parts in closed 65 relationship; Fig. 3 is a sectional end view of the parts, the section being taken on the line 3—3 of Fig. 2; Fig. 4 is a partial plan view of the parts in the same position as is shown in Figs. 2 and 3; and Fig. 5 is an 70 enlarged diagram illustrating graphically the movement of the cutting and shaping knives and the driving parts thereof.

In the construction and arrangement of parts illustrated in the above figures, 1 75 indicates a chamber containing a large supply of molten material of a viscous character, such, for instance, as glass, 2 a delivery orifice in the bottom of said chamber, and 3 a plug which is movable vertically in 80 the orifice 2, and serves to regulate the flow of molten material from the said orifice. At the lower end of the orifice 2, I preferably place a ring 4 of manganese steel, or of some similar, electricity-conducting, material having a low heat conductivity. When such a ring is used, I support it in a water-cooled boss 5 in such manner as to permit of its ready removal and replacement.

The mechanism which I use for severing 90 the stream of material flowing from the orifice 2 is placed closely adjacent the lower side of that orifice; and in the form of mechanism which is illustrated it comprises two blocks 6 and 7 mounted on carriages 95 8 and 9 that reciprocate longitudinally in ways 10 and 11 (see Figs. 3 and 4). The blocks 6 and 7 are preferably formed of manganese steel, and are each provided with cup-shaped cavities 12 and 13 that are approximately semi-circular in horizontal cross section (see Fig. 4) and semi-ovate in vertical cross section (see Figs. 1, 2 and 3). The exterior faces of the blocks at the ends adjacent the cavities 12 and 13 are shaped to a corresponding semi-ovate cylindrical form, and attached to the block 7 is a cutter blade 14 whose inner face is shaped to fit

the outer faces just described. Attached to the carriage 8 are two rods or tubes 15 and 16 which extend forward to a cross head 17 that fits closely between the ways 10 and 11, 5 and is coupled to a crank disk 18 by means of the connecting rod 19. The carriage 9, which carries the block 7 and its attached cutter blade 14, is coupled directly to a piston 20 by means of a rod 21, which also 10 carries a rack 22 that engages with teeth on the pinion crank disk 18. A spring 23 interposed between a lug on the guideway frame 10-11 and an opposing lug on the rod 21, serves to keep the parts of the cutting 15 mechanism normally in the position shown in Fig. 1.

The operation of the above-described mechanism is as follows: With the parts in the position indicated in Fig. 1, the 20 stream of molten material is allowed to flow directly downward from the orifice 2 into the receiving mold or receptacle 24, until the required amount has accumulated in this receptacle. The three-way valve 25 is then 25 operated by the action of a cam 26, which is mounted at some convenient point on the power shaft of the apparatus which supports and controls the movements of the mold receptacles. The opening of this valve admits 30 compressed air or steam or other actuating fluid to the cylinder containing the piston 20, and moves this piston forward against the pressure of the spring 23.

The forward movement of the piston 20 35 produces a simultaneously uniform forward movement of the carriage 9, and also produces—through the engagement of the rack 22 with the crank pinion disk 18—a varying differential reverse movement of the 40 carriage 8. The relation between these opposing movements is shown graphically in the enlarged diagram of Fig. 5, in which the letters *o* and *f* (right hand lower series) indicate successive positions occupied by the 45 ends of the connecting rod 19 and by the edge of the block 6, and the letters *o'* and *f'* indicate successive positions occupied by the edge of the cutter blade 14. An inspection 50 of this diagram will show that the two blocks 6 and 7 will advance toward each other at a nearly uniform speed until the parts reach the position indicated at *d* on the diagram. From that point on, the carriage 8, which is actuated by the movement 55 of the pinion crank disk 18, remains nearly stationary in position, while the carriage 9 (which is actuated directly by the movement of the piston 15) continues to move forward at the same speed as before. The 60 parts are so adjusted in position that the motion of the block 6 practically ceases when its edge has been brought to the center line *X-X* of the stream and its cup cavity 12 has been likewise brought into shaping 65 engagement with the righthand side of the

stream, as shown in Fig. 2. At this point of the movement the edge of the cutter blade 14 has likewise been brought to the center line *X-X* of the stream, and the continued forward movement of the block 7 carries 70 the cutter blade on past the edge of the block 6—thereby insuring the clean and complete severance of the glass stream—and also brings the face of the cup cavity 13 into shaping engagement with the lefthand 75 side of the stream. When the parts have reached this position—as shown in Figs. 2, 3 and 4—the three-way valve 25 is opened (either by the positive action of the cam 26 or by a spring 25') and the actuating fluid 80 is permitted to escape from the cylinder, thus allowing the parts to be quickly returned to the open position shown in Fig. 1 by the action of the spring 23. If desired, the action of this spring can be aided by 85 placing the three-way valve 25 in communication with a vacuum chamber or with some suction device—such as an air or steam ejector—thereby withdrawing the air or actuating fluid from behind the piston 20 and utilizing the exterior atmospheric pressure to 90 return the piston to its initial position.

Both the closing and the opening movements of the cutting and shaping parts are so rapidly performed that the contact between the parts of the glass stream and the metal of the blocks 6 and 7 and the knife 14 is only momentary, and there is no appreciable chilling of the glass from such a contact. The attainment of this result is 95 facilitated by making the blocks 6 and 7 and the blade 14 of manganese steel, or some similar metal, which has an exceedingly high heat resistivity and therefore will conduct away very little heat even when its contact with the glass is quite prolonged. For this reason, the ordinary water-cooling 100 of the metal parts of the cutting mechanism is in many cases unnecessary; but in the apparatus illustrated, I have shown 105 means for introducing circulating currents of water to the cored cavities of both the blocks 6 and 7, without the use of any flexible pipes such as are commonly employed 110 with moving parts of this character. In this 115 case, the water or other cooling fluid is led to and from the cavity in the block 6 through the interior of the hollow rods or tubes 15 and 16, which communicate with elongated ports in the end faces of the cross 120 head 17 and these ports communicate in turn with openings at the ends of the pipes 27 and 28 entering the fixed guides 10 and 11. The cooling liquid is likewise led to and from the cavity in the block 7 through 125 elongated ports 29 and 30 in the carriage 9; these ports communicate with openings at the ends of the fixed pipes 31 and 32.

When a stream of glass or other similar thermoplastic material is delivered from a 130

source of supply, especially when that delivery takes place through a downwardly presented opening or orifice, there is a surface chilling of the stream throughout its entire 5 length, this surface chilling resulting, immediately adjacent and below the discharge orifice in a conical shell, the base of which, immediately adjacent the orifice, is of appreciable thickness and of considerably less 10 plasticity than the interior of the stream, the thickness and character of this shell depending very largely, of course, upon the character of the glass, its initial temperature as it emerges from the furnace, and the 15 atmospheric temperature. Through this tubular shell, the main body of the stream of glass flows, the downward velocity of the middle of the stream being greater than the exterior. I have discovered that when a 20 stream of glass is severed, as above described, at a point fairly close to the delivery orifice, the momentary chilling at the cutting plane results in the completion of an inclosing stream-retarding envelop for the 25 depending end of the stream, the slight chilling resulting from the cutting operation connecting up with the chilled skin or shell which is depending from the discharge orifice. The exact distance of the cutting plane 30 from the orifice will, of course, depend upon the size of the stream, its consistency, temperature and consistency of the inclosing shell, and this distance may be increased by the shaping of the severed end of the stream 35 to a globular or ovoid form, and it is for this reason that I preferably use the shaping blocks 6 and 7 and I also preferably mount the frame of the cutting mechanism on vertical ways—such as 33—thus permitting it 40 to be adjusted up and down so as to secure the best results in different cases.

In general, I have found that the plane of cutting should be located at a distance below the orifice 2 which is approximately equal to 45 the diameter of the said orifice, but this distance, as already stated, can be varied to a considerable degree according to the temperature of the material. When cut at too high a point the glass drop or globule depending from the orifice will not contain a 50 sufficient mass of molten metal to overcome the surface tension and viscosity of the material, and the flow will not be properly re-established after the severing operation. 55 When cut at too low a point, the mass of depending material will be too great and the downward flow will be resumed before a sufficient interval has elapsed for the removal of the filled mold and the bringing of 60 an empty mold—such as 34—to the required charging position. But by adjusting the plane of the cut by the upward or downward movement of the apparatus, a point can be always found where the physical 65 causes tending to control the resumption of

the flow of the severed stream will so cooperate as to support the globular mass depending from the orifice 2 for a sufficient length of time to permit of the necessary mold movements, and will then allow the 70 stream to resume its flow to the next mold.

In order to make the time interval during which the flow must be arrested as short as possible, I prefer to employ the system of moving molds, which forms the subject matter of my copending application, Serial No. 834,233, in which a metal mold—such as 34—is brought directly under a mold—such as 24—which is being filled, and which is, therefore, directly in line with the flowing 80 stream and in position to receive the latter as soon as the filled mold has been moved laterally away from the charging position by its own semi-diameter. The herein described method of controlling the flow of 85 glass is not, however, dependent upon the employment of this or any other particular system of mold movement but may be employed in connection with many different types of glass forming apparatus, in which 90 the different molds of a series are brought successively to the filling or charging position in the present well-known manner.

In some cases—such as those in which the glass is being supplied to the molds at an 95 unusually low working temperature—I find it desirable to employ means for constantly or intermittently heating the material which flows through the orifice 2. This can be conveniently and effectively done by passing an 100 electric current through the glass filling this orifice. For this purpose, I embed a metal terminal or electrode 35 in the end of the regulating plug 3, and connect the terminal with one side of an electric circuit from a 105 constant current generator, such as is employed, for example, in arc lighting. The other terminal of the generator is connected through a switch 36 with the plate 5 in which the flow-ring 4 is mounted. The 110 opening and closing of the switch 36 is controlled by a cam 37 on the power shaft of the machine, and when the circuit is closed intermittently, the parts are so arranged that the current will preferably pass 115 through the glass at the time when it is resuming its flow after each severing operation.

The heating effect produced by a current of constant amperage is itself automatically 120 varied by the temperature of the glass, for the reason that the resistance of the molten material varies inversely with its temperature, while the heating effect varies directly as the resistance of the material. The result 125 is that the colder portions of the glass will be heated to a greater extent than the hotter portions, and uniformity of temperature will thereby be maintained. The passage of the current through the block 4 also serves 130

to sensibly heat that block—since the electrical resistance of manganese steel is extremely high—and this, in turn, serves to reduce the retarding effect of the block on the flow of the stream by reducing the viscosity and surface tension at the bounding surfaces thereof. The employment of an intermittently flowing current in conjunction with the other previously described steps of my improved operation may, therefore, be of decided advantage in such cases as I have already referred to; *i. e.*, cases in which it is desired to deliver the glass to the mold receptacles at the lowest possible working temperature—in a homogeneous physical condition—so as to facilitate subsequent forming operations.

I claim as my invention:

1. A cutter for streams of viscous materials, said cutter comprising a pair of mating cutting members designed for overlapment, means for moving said members toward each other upon opposite sides of the stream inwardly at substantially the same relation to the axis of the stream substantially to the axis of the stream and for continuing the movement of one of said mem-

bers after the other has substantially come to rest.

2. An apparatus for cutting streams of viscous materials comprising a pair of cup-shaped mating members one having a cutting edge and the other having a projecting cutter overlappable upon the first-mentioned cup, means for reciprocating the last-mentioned member toward and from the axis of the stream, a rack associated with said member, a pinion meshing with said rack and carrying a wrist pin, and a link connecting said wrist pin with the other reciprocating member of the cutter for the purpose set forth.

3. An apparatus for cutting streams of viscous materials comprising a pair of cup-shaped mating members one having a cutting edge capable of entering the stream and the other having a projecting cutter capable of entering the stream overlappable upon the first-mentioned cup.

In witness whereof, I have hereunto set my hand at Pittsburgh, Pennsylvania, this eighteenth day of June, A. D. one thousand nine hundred and eighteen.

FRANK L. O. WADSWORTH.
